UNITED STATES PATENT OFFICE.

ALONZO R. MORGAN, OF NEW YORK, AND GARDNER L. MORRISON, OF BROOKLYN, ASSIGNEES TO THE OPEN STOVE VENTILATING COMPANY, OF NEW YORK, N. Y.

FIRE-PLACE HEATER.

SPECIFICATION forming part of Letters Patent No. 234,921, dated November 30, 1880.

Application filed August 18, 1880. (No model.)

To all whom it may concern:

Be it known that we, ALONZO R. MORGAN and GARDNER L. MORRISON, of New York and Brooklyn, respectively, State of New York, have invented new and useful Improvements 5 in Fire-Place Heaters, of which the following is a specification.

The principal part of the invention is an improvement upon the invention of Wm. L. Phillips, patented January 13, 1874, reissued January 12, 1875, and the improvement thereon patented by A. R. Morgan, December 17, 1878; and it relates, mainly, to the reverberatory or expanding chamber interposed between the fire-box and the smoke-flue and inclosed by the surrounding jacket. It is designed to effect a better and more compact arrangement of the reverberatory or expansion chamber in relation to the fire-box and inclosing-jacket, to constitute a portable furnace or fire-place heater alike applicable to fit in an ordinary fire-place of an open coal-grate, or to set out in the room like a stove, and while being more compact, simpler, and cheaper, and requiring less room 25 than as before arranged, yet not being correspondingly diminished in the capacities of its parts—that is to say, by the improved arrangement of the parts within the limited space of the fire-place and in conformity or adaptation 30 to said space as well as to each other, the space is utilized better, so that while the size of the heater is reduced as a whole, so as to be more readily located and fitted into the limited space of a fire-place, the fire-box and expansion-chamber are both more capacious than they 35 could be in the other arrangement of the same size as a whole.

This part of the invention also comprises an arrangement of a regulating-valve in connection with a deflecting-plate in the expansion-chamber, by which there is contrived a variable throat within the chamber similar in operation and effect to that of the top of the fire-place of an ordinary coal-grate, but, owing 40 to its location within the chamber and beyond the top of the fire-box, giving much better results; and it also comprises an arrangement, with the open front or top plate through which the heated air escapes into the room, of a 45 damper located within the jacket behind the said open plate, by which to admit the hot air

into the room or cause it to ascend to the room above.

Another part of the invention consists of the said inclosing-jacket itself, incased with 55 non-conducting material adapted and arranged to retain the heat within the jacket and prevent the absorption of the large amount of heat by the surrounding brick walls now 60 wasted in them.

Figure 1 is a sectional elevation of our improved heater taken from front to back. Fig. 2 is a horizontal section on line *xx* of Fig. 1.

A represents the fire-box; B, the reverberatory or expansion chamber, and C the inclosing-jacket surrounding the same, except the front opening of the fire-place, for causing air entering at any suitable opening or openings, D, at or near the bottom to circulate against and around the walls of the fire-box and expansion-chamber, for being heated on its passage into the room through openings at the front E at the top of the jacket C, or into upper rooms through flue d, to which suitable openings in the top of jacket C will admit it 75 when required. To locate this expansion-chamber wholly on the top of the fire-box, as in the arrangement of Phillips, before referred to, makes the heater too high to enter the fire-place under the arch E' and ordinary mantel-opening. To project it wholly backward from the top of the fire-box with a connection extending therefrom into the side of the chamber, as in the arrangement of Morgan, makes 80 too much depth from front to back.

Now, we propose to construct the chamber B in the same dimensions and form at the opening into it as the top of the fire-box, (see Fig. 2,) and attach or join it directly thereto at or about the place of the joint F, and 90 shape it so as to curve upward, backward, and downward behind and below the top of the fire-box, as shown in Fig. 1; also, to expand laterally, as shown in Fig. 2, by its lateral sides I', to utilize all of the available space at 95 the top, sides, and back, and also as much of the space left by the forward slope of the upper part of the back G of the fire-box as is consistent with a suitable distance between back G and bottom or back plate, H, of the 100 chamber B, for circulation of the fresh air to be heated, this being effected by giving the

same, or about the same, slope to plate H as that of plate G, the two being parallel, or thereabout, below the turn of the top of plate H, where it joins the top of the fire-box and makes a bridge, H', between said fire-box and the lower portion of the chamber. The plate I of the chamber B, which forms the front, top, and back of said chamber, curves from the front to the top, then projects a suitable distance back, and then drops vertically in a line but little in rear of the greatest back projection of the fire-box.

The connection of the chamber B with the fire-box by the joint F is directly at the point of the greatest forward projection of the back G and where the contraction between said back and front G' is greatest, and the expansion of the chamber begins directly above this point, extending in the lateral upward, backward, and downward direction shown, whereby it is evident that much is gained in the way of contraction of the whole without corresponding diminution of the fire-box and expansion-chamber.

25 The joint F need not necessarily be at the point where the chamber B begins, for the plates of the fire-box may be so extended in, or about in, the lines of the plates H and I, also the sides I' of the chamber, as to extend 30 the joint farther up or over the top, if desired; but the expansion should begin at the said point by such formation of the plates of the fire-box when so extended to locate the joint farther up.

35 The collar J, for the connection of the smoke-pipe K, is preferably fixed a little back of the top of chamber B, with a short pipe-section, L, going obliquely through the jacket to receive the smoke-pipe, as shown, so that in fitting a heater into a fire-place, the pipe K being temporarily fixed in its place, the collar or section L may be pushed into it at the same time that the heater is shoved into its position in the fire-place; but the collar may be 45 arranged to connect with a straight upright pipe, if preferred.

To deflect the escaping products of combustion in the expansion-chamber and retard their escape to favor their expansion and increase their action upon the walls of the expansion-chamber, the deflecting-plate M is attached to the top of the chamber in advance of the passage W, for the escape to the smoke-pipe, and so as to turn them down into the 50 part of the chamber behind the fire-box; and for the regulation and control of the draft we have located the damper N at the bridge H', formed by the junction of back plate, H, with the top of the fire-box back plate G, over 55 which the products of combustion pass into the lower part of the chamber, and so as to work to and from the lower edge of this deflecting-plate, whereby the effect is much better than when located at the top of the back 60 of the fire-box to work in connection with the front, as is usual in fire-places, because all the

advantages of that part of the expansion-chamber in front of the damper are secured to the gases retained or retarded by it, whereas they would escape more rapidly and directly 70 through the chamber if the damper were located in the usual place.

The rod X is employed to work and hold the damper, and the arrangement is such that when wide open the damper falls onto plate 75 H and allows free passage into the lower part of the chamber for the products of combustion.

The openings at E through the front for the escape of the heated air from the inclosing-jacket C into the room are separated or partitioned off from the rest of the space in the jacket by the plate a, which contains a register of pivoted fans or wings b, to shut off the air from going through openings E, and cause it to ascend the flue d to rooms above, when 85 required. The handle f, projecting out through a slot in the front, is used to work the register.

By employing this kind of damper or register instead of the common slide in the front 90 plate we have larger openings for the escape of the hot air, because the slide can only open half the area, while this opens nearly the whole, and by locating it in the partition behind the front plate the unsightly fans are 95 properly concealed.

g represents the non-conducting material—such as asbestos, paper, or felting, or other equivalent material—and a thin retaining sheet of metal with which we inclose the jacket to 100 prevent the escape of heat into the walls of the fire-place, which is a source of great loss to other fire-place heaters. We apply this non-conducting jacket to all heaters intended for being set up in fire-places, when making 105 them as part of their construction, so that the purchasers will obtain them already prepared to put in place.

By this attachment we save a large percentage of heat heretofore lost by absorption 110 into the walls of the fire-place, where it is wholly wasted.

Having thus described our invention, what we claim, and desire to secure by Letters Patent, is—

1. The combination, with the fire-box A of an open-front stove or heater and a jacket, C, thereto, of the reverberatory chamber B, constructed and arranged as hereinbefore described—that is, being connected at and coinciding in form with the top and contracted portion of the fire-box, expanding laterally, rearwardly, and vertically therefrom, one portion or plate of the shell extending from the point of its connection with the back of the fire-box down along and parallel with the forward slope of said back, and another portion or plate arching from the point of its connection with the front of the fire-box rearward beyond the aforesaid part, connecting with the 125 back of the fire-box, and then extending downwardly parallel with and in near proximity to

the back of the jacket to the point, or thereabout, of connection with said other part.

2. The combination, with the fire-box A and the expansion or reverberatory chamber B, having the deflecting-plate M projecting from the top in front of the smoke-passage, of the damper N, located at the bridge between the top of the fire-box and the lower part of said chamber and under the deflecting-plate, 10 substantially as set forth.

3. The combination, with open-front fire-box A, jacket C, and reverberatory chamber B, of the partition *a* and wing or fan registers *b* in said partition, separating the open portion E 15 of the front plate from the space within said

jacket C, wherein the air is heated, substantially as set forth.

4. The improved article of manufacture consisting of a portable open-front stove or heater, having a jacket, C, for causing a circulation 20 of air along and around the fire-box to be heated, and a non-conducting envelope applied as a part of such portable stove or heater, substantially as described.
